METHOD OF AND MEANS FOR THE MODULATION OF ULTRASHORT WAVES

Henri Gutton and Antoine Jean Ortusi, Paris, France, assignors to Compagnie Generale De Telegraphie Sans Fil, a corporation of France

Application July 19, 1946, Serial No. 684,819
In France February 6, 1945

Section 1, Public Law 690, August 8, 1946
Patent expires February 6, 1965

7 Claims. (Cl. 332—55)

1

This invention is directed to improvements in or relating to methods of and means for the modulation of ultra-short waves in a guide or on a feeder by means of space charge valves such as a magnetron, brake field valve and the like. For the purpose of indicating the underlying principle of the invention the same will be described by way of example as applied to a magnetron.

It will be noted, in the first place, that in a blocked cylindrical magnetron the electrons which do not reach the anode circulate in the interior of a cylinder the diameter of which is comprised between the diameter of the cathode and that of the anode and there is a very important electronic charge on the surface of this cylinder.

If there be therefore applied, between the cathode and the anode, an electric field of high frequency, the electrons of the spacial charge oscillate radially following the frequency of the field. Theory and experience show that this oscillation is capable of entering into resonance with a particular frequency depending upon the amount of the magnetic field H , the pulsation of the resonance frequency being approximately

$$\omega_0 = \frac{eH}{m'm}$$

indicating the ratio of the charge to the mass of an electron.

Theory and experience also show that in the vicinity of the resonance the apparent capacity of the magnetron varies very rapidly when the pulsation ω of the field of high frequency varies on each side of ω_0 . On the other hand, the density of charge in a cylindrical space surrounding the cathode is a function of the anode potential; and the variation of apparent capacity of the magnetron is itself a function of the anode potential, when the pulsation ω of the field remains constant.

The invention will be more particularly described with reference to the accompanying drawings, in which:

Figure 1 illustrates diagrammatically a device of a transmitter feeding a system radiating through the intermediary of a feeder coupled to a resonator;

Fig. 2 represents the variations of the coefficient of transmission of the wave corresponding to the detuning d of the resonator;

Fig. 3 illustrates, corresponding to a potential V of the anode, variation curves of the transmission coefficient for different values of the magnetic field;

2

Fig. 4 illustrates a complete embodiment of the invention; and

Figs. 5 and 6 illustrate the arrangement of a few details.

Referring to the drawings a transmitter E (Fig. 1) transmits energy to a radiating system K through the intermediary of a feeder G preferably formed by an electromagnetic guide. The guide G traversed by a progressive wave, is coupled to a resonator r formed, for example, by a line terminated at its extremity by the capacity C of a magnetron. On tuning the resonator r to the transmission frequency and suitably selecting its excess potential on load, there may be obtained the almost total reflection of the incident wave. The curve representing the coefficient of transmission T of the wave as a function of the detuning d of the resonator therefore assumes the form illustrated in Fig. 2. It shows all the more pointedly that the looser the coupling of the resonator to the feeder, so the coefficient of transmission may pass from a value very close to 1, at A, to a value very close to 0, at B, and this all the more suddenly the greater the modification of the capacity C of the resonator about the resonance.

With such a resonator r , it has been possible to obtain experimentally the group of curves shown in Fig. 3. There is shown in abscissae the anodic potential V applied to the magnetron of the resonator and in ordinates, the coefficient of transmission T of the resonator. Each curve of the group corresponds to a value of the magnetic field H , expressed in gauss, a value close to that of the magnetic field causing the resonance. The value t of the transmission coefficient corresponds to the case where no potential is applied to the anode. There will preferably be chosen a mean potential v corresponding to a mean point M located on a characteristic ab' and the modulation will be obtained by applying to the anode of the magnetron a variable potential the amplitude of maximum variation of which will be equal to $av-bv$.

As will be seen from Fig. 3, the preceding group comprises curves that are almost linear, thus permitting very important rates of modulation of the order of 80%, without appreciable distortion to be obtained.

On the other hand, the modulator magnetron may be of comparatively small capacity, so that its impedance remaining large at high frequencies of modulation, it permits, without appreciable attenuation, the modulation of, for example, very rapid television signals.

Finally, a particularly important advantage of the system according to the present invention is that the magnetron modulates the transmitter without absorbing energy. The characteristics of Fig. 3 have, in fact, all been drawn for potentials very much below the potential necessary to unblock the valve and practically necessary the anode current never exceeds 1 milliampere.

It is thus for example that for a magnetron which had a cathode of a diameter of 4 mm. and an anode of 10 mm. it has been found that to modulate a wave of 20 cm. it was necessary to use a magnetic field approximating to 500 gauss and an anode potential of 250 volts, the amplitude of the potential of modulation being equal to 125 volts to obtain a total modulation. In this case, the energy necessary for the modulation obtained with a pentode of low reception frequency, was of the order of only 0.5 watt.

But about half the mean energy conveyed by the incident wave is returned to the transmitter; the result is a modification of the charge of the generator. To avoid this, the invention provides a double modulator the principle of which is as follows:

The transmitter is charged on two feeders, or two electromagnetic guides, in such manner that each of these transmits half the energy. Symmetrically there are coupled two resonators on each of these guides. The capacities of these resonators each comprise a magnetron the anode potential of which is modulated. The first magnetron receives the modulated potential to be transmitted and the second a complementary potential in such manner that the sum of these two potentials remains constant. Under these conditions, the transmitter supports a constant charge.

The methods which permit these two complementary modulations to be obtained are, furthermore, numerous; for example, a transformer the secondary of which has a central point earthed, may be used for the transmission of telephonic signals; or, again, an amplification may be made in push-pull, etc.

When it is a matter of sinusoidal signals or of telephonic signals, one or other of the complementary modulations may be transmitted indifferently to the radiator; if it is a question, on the contrary, of the transmission of television signals, only the wave correctly modulated can be used to transmit to the aerial. The complementary modulated wave is eliminated by terminating the guide which transmits it by its characteristic impedance; this can be effected either by a radiator fitted to the extremity of the guide, which radiator radiates the energy in a direction other than that of the receiver, or by a resistance fitted at the extremity of the guide.

For certain problems of radio guidance two complementary modulations transmitted by two different aerials, the diagrams of radiation of which intersect each other, are frequently used. In such systems it is very advantageous to employ this method of modulation, for the complementary modulations can be very rapid since there is no mechanical permutation at all.

It has been pointed out at the commencement that this method of modulation may be utilized with other kinds of valves, in which the capacity in high frequency between two electrodes undergoes variations when the potential of one of the electrodes varies as compared with the other. In particular, the magnetron can be replaced by a valve with brake field; there exists, as a matter

of fact, in this valve, as in the magnetron, a space charge capable of resonating at a definite frequency; the effect produced by causing the potential of the retarding plate or that of the accelerating grid to vary, is similar to that observed with the magnetron.

Naturally, it is impossible to describe all the forms of carrying the invention into effect. By way of a non-restrictive example, one of these will be described.

The transmitter E (Fig. 4), for example, a velocity modulation valve, is coupled to a guide G of rectangular section which can only transmit the wave H_{01} on the frequency of the transmitter. Coupling takes place by a radiating aerial in the interior of a guide element closed on one side by a piston P, and on the other side by a suitable slot F. The whole is fitted in such manner that the transmitter is charged under the desired conditions.

The preceding guide is separated into two guides 1 and 2, by the interposing of a metallic partition Q. Arrangements are made so that there should be no reflection on the incident wave 25 on this discontinuity. This may be accomplished by annulling the reflection by a suitable adaptor D. Half the incident energy then circulates in each of the guides 1 and 2.

This being so, the energies transmitted by 30 guides 1 and 2 will be modulated complementary by using two concentric lines L_1 and L_2 arranged symmetrically and the central conductors of which are placed in communication with the metallic wall Q through a flat condenser 35 S. At the other extremities of the concentric lines there are connected two identical magnetrons M_1 and M_2 the anodes a_1 and a_2 of which are respectively connected to the central conductors of L_1 and of L_2 , and the cathodes β_1 , β_2 of which are respectively in connection with the external parts of L_1 and L_2 . In Fig. 4, there are shown furthermore at μ_1 , μ_2 the magnets of the magnetrons, and by γ_1 , γ_2 , their respective heating circuits. As regards Fig. 5, it gives the details of the connections of each of the magnetrons M_1 or M_2 .

On the other hand, the anode potentials of the two magnetrons M_1 and M_2 on which are superposed the modulation potentials, are produced by means of two conducting wires f_1 , f_2 (Fig. 6) arranged normally to the elastic field φ , and connected respectively to the two electrodes of the condenser S; these wires f_1 and f_2 emerge furthermore from the guide through an insulator.

Fig. 6 represents a section of Fig. 4, which section is made perpendicularly to the plane of the latter, at the level of the condenser S.

Finally, the branch 1 of the guide (Fig. 4) which has received the modulation suitable to be transmitted, is terminated by the radiator K, which is an electromagnetic horn adapted by a suitable corrector D_1 ; whilst the branch 2 which receives the complementary modulation from 1, is terminated by a resistance R adjusted by means of a slot F_1 and a piston P_1 suitably actuated.

According to this example of the embodiment 70 of this invention, there can be seen the principal advantages of the modulation of the ultra-short waves.

1. The transmitter not being modulated, its stability of frequency remains very high, and its 75 point of operation can be chosen under the best

conditions; in general it will therefore be useless to pilot it.

2. The modulation may be very rapid, since it is only limited in the direction of high frequencies by the capacity of the electrodes of the modulator; it will thus be possible for example to pass television signals. However, the transmitter not being modulated, the modulation band will not have to pass into the circuits of the high frequency generator which consequently may preserve great supertension favorable to output and to the stability of the generator wave.

3. The energy necessary for modulating powers which may be of several hundreds of watts, remains very slight, of the order of a watt, for this energy is only used to modify the capacity of the valve by displacement of the space charged.

4. The modulator does not absorb the energy coming from the transmitter; it can thus be of small dimensions and consequently of very low cost price.

5. The energy furnished by a single generator can be delivered into a large number of feeders or of guides, and modulate in a totally independent manner on each of these guides. This may be utilized to produce a multiplex having a large number of paths.

What we claim as our invention and desire to secure by Letters Patent of the United States is:

1. A system for the modulation of an ultra-high frequency wave, comprising a generator of the said wave, a transmission guide for said wave, a transmission line connected laterally to the said guide, a magnetron including an anode and cathode, connections between said magnetron and said line, the characteristics of the said line and of the said magnetron being chosen in such a way that their aggregate resounds on the frequency of the said wave, means connected with the said magnetron for varying the direct voltage between the anode and cathode of the said magnetron means for applying a continuous potential between the anode and the cathode of said magnetron, regulated in such a way that the latter is in the blocked state, and means for applying a variable potential in series with the said continuous potential, said variable potential being regulated in such a way as to maintain the tube in the blocked state.

2. A system for the modulation of an ultra-high frequency wave, comprising a generator of the said wave, a transmission guide for said wave, a transmission line connected laterally to the said guide, a magnetron comprising a cathode, an anode concentric with the cathode, and a magnetic field directed along the common axis of the said anode and of the said cathode, means for varying the voltage between the anode and the cathode of the said magnetron, means connected with the said magnetron for giving to the said magnetic field a value slightly different from the value which determines the electronic resonance of the space charge of the magnetron on the frequency of the wave to be modulated, means for applying a continuous potential between the anode and the cathode of said magnetron, regulated in such a way that the latter is in the blocked state, and means for applying a variable potential in series with the said continuous potential, said variable potential being regulated in such a way as to maintain the tube in the blocked state.

3. A system for the modulation of an ultra-high frequency wave, comprising a generator of the said wave, a transmission guide for said wave, a conductive wall separating the said guide into

two other guides, a transmission line, connected laterally to one of said two guides, a magnetron connected with the said line, and comprising a cathode, an anode concentric with the cathode, and a magnetic field directed along the common axis of the said anode and of the said cathode, another transmission line connected laterally to the second guide, another magnetron connected with the said line and comprising a cathode, an anode concentric with the cathode, and a magnetic field directed along the common axis of the said anode and of the said cathode, means connected with the said magnetrons for giving to the said magnetic fields values slightly different from the values which determine the electronic resonance of the space charges of the magnetrons on the frequency of the waves to be modulated, and means connected with the said magnetrons for applying between their electrodes modulation voltages equal in amplitude and opposite in phase.

4. A system as set forth in claim 3, wherein the modulator magnetrons are identical and are of the cylindrical type with full anode.

5. A system for the modulation of an ultra-high frequency wave comprising a generator of the said wave, a transmission guide for said wave, a transmission line connected laterally to the said guide, a magnetron including an anode and cathode, connections between said magnetron and said line, the characteristics of the said line and of the said magnetron being chosen in such a way that they conjointly resonate at the frequency of said wave, means for applying a continuous potential between the anode and the cathode of said magnetron regulated in such a way that the latter is in the blocked state, means for applying a variable potential in series with the said continuous potential, said variable potential being regulated in such a way as to maintain the tube in the blocked state, means for establishing a magnetic field parallel to the cathode and means for regulating said field in such a way that it is slightly different from the field determining the electronic resonance of the space charge on the wave to be modulated.

6. A system for the amplitude modulation of an ultra-high frequency wave, comprising in combination a generator for supplying an ultra-high frequency wave, a transmission guide for said wave, a circuit tunable to this wave composed of a transmission line coupled laterally to the said guide and a magnetron including a cathode, an anode concentric with the cathode, and a magnetic field directed along the common axis of the said anode and the said cathode, means for applying a continuous potential between the anode and the cathode of said magnetron, regulated in such a way that the latter is in the blocked state, means for applying a variable potential in series with the said continuous potential, said variable potential being regulated in such a way as to maintain the tube in the blocked state, and means for regulating said magnetic field in such a way that it is slightly different from the field determining the electronic resonance of the space charge on the wave to be modulated.

7. In a system for amplitude modulation of an ultra-high frequency wave circulating in a transmission channel such as a guide, a circuit tunable to the said wave coupled laterally with said guide, a magnetron in this circuit comprising a cathode and an anode surrounding it, means for introducing a magnetic field between said cathode

and anode, means for energizing the said magnetron, all of said means being adjusted so as to maintain the magnetron in a blocked state, means for applying the modulating voltage between said anode and cathode the amplitude of which is adjusted so as to maintain the magnetron in said blocked condition, the said magnetic field being given an intensity slightly different from that determining the electronic resonance of the space charge to the wave to be modulated.
